UNITED STATES PATENT OFFICE.

HARRY R. COREY, OF BROOKLYN, NEW YORK, ASSIGNOR TO AMERICAN CAN COMPANY, OF NEW YORK, N. Y., A CORPORATION OF NEW JERSEY.

DESIGN FOR A TALCUM-POWDER BOX.

52,472.

Specification for Design.

Patented Sept. 24, 1918.

Application filed September 20, 1913. Serial No. 790,955. Term of patent 14 years.

To all whom it may concern:

Be it known that I, HARRY R. COREY, a citizen of the United States, residing at 519 Fifth street, Brooklyn, in the county of Kings and State of New York, have invented a new, original, and ornamental Design for Talcum-Powder Boxes, of which the following is a specification, reference being had to the accompanying drawing, forming part thereof.

In the drawing, Figure 1 is a side eleva-

tion, Fig. 2 a top plan view and Fig. 3 an edge elevation of a talcum powder box showing my new design.

I claim:

The ornamental design for a talcum powder box, as shown and described.

HARRY R. COREY.
